OILING SYSTEM FOR INTERNAL COMBUSTION ENGINES

Perry E. Mack, Milwaukee, Wis., assignor to
Briggs & Stratton Corporation, Milwaukee,
Wis., a corporation of Delaware

Application January 31, 1934, Serial No. 709,167

2 Claims. (Cl. 184—6)

This invention relates to certain new and useful improvements in lubricating systems for internal combustion engines, and has as an object to provide means for positively projecting a lubricant up into the cylinder and piston to simultaneously lubricate these parts and cool the piston.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention, may be made as come within the scope of the claims.

In the accompanying drawing, I have illustrated one complete example of the physical embodiment of my invention, constructed according to the best mode I have so far devised for the practical application of the principles thereof, and in which:

The single figure is an end view of an internal combustion engine with parts broken away and in section and illustrating the application of this invention thereto.

Referring now to the accompanying drawing, the numeral 5 represents generally the crank case of the engine illustrated, which rests on and is closed by a base 6 adapted to hold a supply of lubricant. A cylinder block 7 is secured to the upper portion of the crank case with its bore 9 communicating with the interior of the case. A piston 8 operates in the bore 9 and is connected through a rod 10 with the crank shaft 11 in the customary manner.

Alongside the cylinder are the intake and exhaust valves of the engine, which, as is customary, are operated from a cam shaft 12, disposed within the crank case 5.

In the conventional small gas engine to which this invention is particularly directed, the lubrication of the engine parts is generally accomplished by the splash system, the oil being splashed up onto the operating mechanism by the connecting rod and crank shaft dipping down into the oil contained within the crank case.

While this system generally affords adequate lubrication, this invention contemplates the provision of means for positively supplying oil to the piston and cylinder, which are the parts most difficult to lubricate properly by the splash system. Besides augmenting the lubrication of these parts, the present invention also simultaneously effects a cooling of the piston.

These objects are attained by providing a small force pump 13 of any suitable construction, and located so that its intake is submerged within the oil in the crank case. The outlet of the pump has a discharge tube 14 leading up into the cylinder with its discharge end 15 arranged to spray oil up into the cylinder and into the inside of the piston.

The pump 13 is operated by a plunger 16 projecting upwardly therefrom and guided at its upper end by a stationary guide bracket 17. The plunger 16 is located alongside the cam shaft 12. A cross arm 18 is secured to the plunger with one end under the cam shaft to be engageable by a cam 19 fixed to the cam shaft, whereby reciprocation of the plunger 16 is effected during operation of the engine, a spring (not shown) within the pump, yieldably urging the plunger upwardly to maintain its arm 18 in engagement with the cam 19. The opposite end of the cross arm 20 has an upstanding stem 21, which is also slidably received in the guide bracket 17 to hold the plunger against turning and maintain the cross arm in engagement with the cam 19.

During operation of the engine, the reciprocation of the plunger 16, effected in the manner hereinbefore described, causes the pump 13 to draw oil from the supply within the crank case and force it outwardly from the mouth 15 of the discharge tube 14 upwardly into the cylinder and against the under-surface of the piston. Consequently, the cylinder walls are positively lubricated and much of the heat developed in the piston is carried off.

It is to be observed that the cam 19 is so fixed on the cam shaft 12 that the pump plunger 16 is moved in its compression stroke to effect the expulsion of the lubricant from the mouth 15 only during the power stroke of the piston 8.

What I claim as my invention is:

1. In an internal combustion engine having a piston operating within a cylinder, a cam shaft and a crank case to contain a supply of lubricant, a force pump mounted within the crank case and arranged to take lubricant from the supply contained within the crank case, a discharge pipe for the force pump extending from the pump to the mouth of the cylinder to direct a spray of lubricant up into the cylinder and against the under-side of the piston, and means to operate the pump from the cam shaft of the engine comprising a plunger for the pump having a part in juxtaposition to the cam shaft, a fixed guide in which the plunger is slidably received, a cross arm fixed to the plunger, a stem parallel with the plunger

and carried by the cross arm, part of the cross arm forming a cam follower, a cam on the cam shaft engaging said follower to reciprocate the plunger, and guide means to slidably receive said stem to hold the plunger against rotation and the arm in engagement with the cam.

2. In an internal combustion engine having a piston operating within a cylinder, a cam shaft and a crank case to contain a supply of lubricant, a force pump mounted within the crank case and arranged to take lubricant from the supply contained within the crank case, a discharge pipe for the force pump extending from the pump to the mouth of the cylinder to direct a spray of lubricant up into the cylinder and against the under-

side of the piston, and means to operate the pump from the cam shaft comprising a cam on said cam shaft, a plunger for the pump having a portion in juxtaposition to the cam, a fixed guide in which the plunger is slidably received to be held thereby in proper relationship to the cam, a lateral arm projecting from the plunger to engage the cam as a cam follower, a second arm extending laterally from the plunger, a stem carried by said second arm in parallel relationship to the plunger, and a fixed guide to slidably receive the stem, said stem acting in its guide to hold the plunger against rotation and maintain the cam follower in engagement with the cam.
